United States Patent Office

Des. 199,813
Patented Dec. 15, 1964

199,813

JUG

Edgar F. Trombly, Grosse Pointe Farms, and Clara Virginia Eicholtz, Midland, Mich., assignors to The Dow Chemical Company, Midland, Mich., a corporation of Delaware

Filed Apr. 22, 1964, Ser. No. 79,656

Term of patent 14 years

(Cl. D58—5)

Fig. 3

Fig. 1

Fig. 4

Fig. 2

Fig. 7

Fig. 5

Fig. 6

FIG. 1 is a side elevational view of a jug showing our new design, and in which the side not shown is the same as the side shown;

FIG. 2 is a top plan view thereof;

FIG. 3 is an end elevational view thereof looking towards the right of FIG. 1;

FIG. 4 is an end elevational view thereof looking towards the left of FIG. 1;

FIG. 5 is a sectional view thereof taken along line 5—5 of FIG. 1;

FIG. 6 is a sectional view thereof taken along line 6—6 of FIG. 1; and

FIG. 7 is a bottom plan view thereof.

We claim:

The ornamental design for a jug, as shown and described.
